CLAIM

The ornamental design for towel with handle, as shown and described.

DESCRIPTION

FIG. 1 shows a top plan view of a first embodiment of the present invention in the form of an elongated towel having handgrips at each end.

FIG. 2 is an end view of the towel shown FIG. 1.

FIG. 3 is a side elevation view of the towel shown in FIG. 1.

FIG. 4 is a top plan view of a second embodiment of the present invention, showing a towel having a diagonal handle in one corner.

FIG. 5 is an end elevation view of the towel shown in FIG. 4.

FIG. 6 is a side elevation view of the towel shown in FIG. 4.

FIG. 7 is a plan view of a third embodiment of the present invention, in the form of a towel having a handle in the middle of one edge of the towel.

FIG. 8 is an end elevation view of the towel shown in FIG. 7; and,

FIG. 9 as a side elevation view of the towel shown in FIG. 7.

Structure, environment, and/or boundaries shown in broken lines form(s) no part of the claimed design.

Some aspects of the towel with handle are shown with symbolic breaks in width and length, wherein the appearance of any portion of the towel with handle between the break lines forms no part of the claimed design.

The broken lines in the drawings show unclaimed portions of the towel with handle and form no part of the claimed design.
